SPHERICAL COMPASS

Kenneth B. Ledgerwood, Dorchester, Mass., assignor to All Hands, Incorporated, Hingham, Mass., a corporation of Massachusetts

Filed Jan. 23, 1962, Ser. No. 168,151
4 Claims. (Cl. 33—223)

This invention relates to a spherical compass.

A spherical compass characteristically includes a compass card carried in a liquid-filled enclosure with generally spherical inner surfaces. The whole point of the spherical inner surfaces is to avoid causing movement in the liquid when the enclosure is moved by movement of the boat or other object carrying the compass, for liquid movement causes undesirable movement of the compass card, which is surrounded by the liquid. Nevertheless, much undesirable liquid movement has been characteristic of so-called spherical compasses heretofore available. Certain of this undesirable movement has been owing to the fact that inner surfaces of enclosures were not in fact substantially spherical, containing on the contrary open relieved portions interrupting true spherical continuity and providing in contact with the liquid enclosure propelling surfaces at angles to tangents to what would constitute the spherical surface if uninterrupted and at even greater angles to the portions of spherical surface immediately adjacent to said relieved portions; these propelling surfaces acted on the portions of liquid adjacent them to drive such portions with the enclosure when the latter moved, thus creating movement and turbulence within the overall body of the liquid. Other undesirable liquid movement has been owing to the fact that expansion chambers have been provided outside the spherical enclosure and communicating therewith through holes providing relieved portions as described; that movement of the boat or other mounting has repeatedly driven additional liquid by inertial effects through such holes into such expansion chambers; that such expansion chambers have typically been elastic, so that when such inertial effects were removed or modified they urged the liquid so moving back through such holes into the spherical enclosure; and that in moving back through such holes, said liquid re-entered the spherical enclosure with a jet-effect directional flow either directly impinging on the compass card (in almost all cases upsettingly non-centrally thereof) to undesirably move it or causing turbulence in the main body of liquid with similar ultimate effect.

It is a primary object of the present invention to protect the compass card against undesirable movement from both effects and tendencies above mentioned. It is a further object to provide an enclosure with a spherical inner surface free from open relieved portions providing liquid-propelling surfaces. A further object is to provide in said enclosure a pivotally mounted indicating assembly which includes not only the compass card and a magnet for driving it but also a compression chamber. Other objects are to provide new and improved simple assembly features, to provide a novel construction additionally insulating the entire enclosure against shocks to and abrupt short-duration movements of the boat or other mounting for the compass, and to provide for improved fore-and-aft pivotal mounting of the indicating assembly.

Other objects, features, and advantages will appear from the following description of the presently preferred

2

embodiment, taken together with the attached drawings thereof, in which:

FIG. 1 is a plan view of said presently preferred embodiment;

5 FIG. 2 is a side elevational view, partially in section, thereof;

FIG. 3 is an isometric view on the enclosure for said embodiment, showing in dotted lines the indicator assembly contained therein;

10 FIG. 4 is a sectional view taken at 4—4 of FIG. 3;

FIG. 5 is a partial sectional view taken at 5—5 of FIG. 3;

FIG. 6 is an exploded isometric view of a novel sub-combination embodied in said preferred embodiment; and

15 FIG. 7 is a sectional view taken at 7—7 of FIG. 4.

Referring now to the drawings in more detail, there is shown a molded plastic skin 10 in which is seated a polyurethane foam cushion 12. The foam is soft and yieldable, like that used in furniture upholstering. For boat use the foam is desirably coated or of closed-cell character, to keep out water. The outer configuration of the foam cushion 12 coincides with the inner configuration of the skin 10 where the two elements are in contact. The inner configuration of the cushion 12 is spherical, to conform with the outer surface of the enclosure 16, where they are in contact. The upper portion of the enclosure 16 extends out through a hole in the upper portion of the cushion 12. The enclosure 16 is formed of two transparent plastic hemispheres, joined by any suitable means, 30 not shown, and is filled with transparent liquid. Said hole in the cushion 12 is of course smaller at its top than the diameter of the spherical enclosure, since said hole conforms to the surface of the spherical enclosure, and cooperates therewith along portions of the surface of the latter well above its equator, indicated by 18. However, the foam cushion may easily be temporarily stretched to seat the enclosure 16 in the hole thereof. Extending all around said hole is a reversely directed lip 20 defining with the main body of the cushion 12 a groove in which 35 is seated the mating edge of the skin 10, said edge defining a circular but non-planar hole, as shown. The edge 22 of the rigid skin 10, assembled into the groove under the lip 20 after the enclosure 16 is in position, likewise defines a hole smaller than the diameter of said enclosure, 40 and positively secures it against displacement in use. The rigid plastic plate 24 secures the cushion 12 against downward displacement relative to the skin 10.

The cushion 12 includes a hole 26 opening into zone 28 defined inwardly by the enclosure 16. This hole and 50 enclosure are to accept a small light assembly (not shown) for illumination of the compass when needed, and plate 24 includes hole 30 for wires therefrom. Secured in the lower hemisphere of enclosure 16 are a pair of flanged brass pins 32 on which is pivotally mounted plastic gimbal ring 34. Pivotally mounted on brass flanged pins 36 55 inside gimbal ring 34 is the indicator assembly, generally indicated at 38.

The pins 32 are port-and-starboard of the compass and the pins 36 are fore-and-aft thereof. It has been found that in modern higher-speed boats mounting the gimbals in this manner, rather than as in the prior art mounting the outer ring on fore-and-aft pins, provides for lessened disturbance of the compass by boat movement.

60 Adhesively secured to the lower hemisphere of enclosure 16 is plastic filler boss 40 accepting filler screw

42, which extends through the enclosure 16, the end of the screw being aligned with the inner surface thereof. A seal is provided by filler gasket 44.

The indicator assembly 38 includes a transparent plastic support member 46 with a pair of upwardly extending mounting portions 48, an annular downwardly extending support portion 50, the inner diameter of which is approximately the same as the compass card diameter, and a transversely extending central portion 52. Centrally of the portion 52 is force-fittedly mounted a brass jewel shaft 54 carrying jewel 56. Supported on the jewel 56 is pivot pin 58, which is force-fittedly held in transparent plastic bushing 60 against movement relative thereto. The bushing 60 has abutment surfaces 62 which rest against the upper surfaces of aluminum compass card 64 and a round shank portion 66 which extends through a mating central hole in the compass card 64 and therebeneath. The bushing 60 also includes, above, alongside, and below the compass card 64 a transversely extending slot 68 to facilitate a resilient gripping effect in the shank portion 66, upwardly through which extends blind hole 70, and to accept the elongated ends of magnet 72. Adhesively secured to the lower surface of compass card 64 is magnet 72, which has parallel flat upper and lower surfaces, a pair of opposed elongated end portions 74 and 76 the latter of which is pointed in a direction corresponding to the direction indicated as north on the compass card thereabove, and an intermediate portion 78 between the said end portions with surfaces constituting portions of a cylinder and mating with the inner surfaces of the slotted blind hole 70 through the shank portion 66 of the plastic bushing, which resiliently grip the cylindrical portions of the magnet to hold the latter and the compass card (held between the magnet and the abutment surfaces 62 of the bushing) against movement relative to the pivot pin 58. The magnet includes a countersunk central hole limiting upward movement of the magnet relative to the jewel shaft 54, which includes a frusto-conical surface cooperating with the similar surface countersunk in the magnet to provide a stop.

Also mounted in support member 46 are lubber's line pins 80.

Adhesively secured to the lower surface of support portion 50 therearound is the flange 82 of upper compression chamber member 84. Adhesively secured to the flange 82 therebeneath is flange 86 of lower compression chamber member 88. The two expansion chamber members are formed from thin transparent cellulose acetate plastic sheet about .008 inch thick, include undulations 90 and 92 for increased flexibility, and define therebetween a sealed air pocket or compressible gas filled compression chamber 94 having a depth less than half its diameter, for improved stability. Extending through the support portions 50 are a pair of holes 95 which permit liquid communication with the top of upper compression chamber member 84.

Secured beneath compression chamber 94 is strap 96 carrying weight 98 selected to tend to stabilize the indicating assembly 38 with the compass card 64 in horizontal position without unduly increasing the weight of the indicating assembly relative to the weight of a corresponding volume of the liquid with which the enclosure 16 is filled.

For use, the enclosure 16 may be filled with liquids of character well known in the prior art through the hole in filler boss 49, temporarily removing screw 42 for the purpose. Any expansion of the liquid with temperature change is accommodated by compression of compression chamber 94. The air inside the sealed compression chamber will expand to increase the volume thereof, on the other hand, in the event of shrinkage in the volume of liquid present.

No open relieved portions interrupt spherical continuity in the improved compass of the present invention, to provide undesirable liquid propelling surfaces upon en-

closure movement. No holes to external expansion chambers through which jets of liquid may surge to undesirably impinge on the compass card and agitate the liquid are present. Furthermore, prevention of undesired disturbance of the compass card is further cooperatively promoted both by the novel gimbaling arrangement inside of the enclosure and by the novel manner in which the enclosure is itself mounted for protection against shocks caused by short duration forces on the boat or other object carrying the compass. Transparency of the upper enclosure hemisphere permits reading the compass, and transparency adjacent the zone 28 permits lighting up the compass, as for night use. The form and relationship of the elements taught, including the bushing-magnet-card subassembly permits easy and trouble-free construction at considerably lowered assembly expense.

Other embodiments of my invention within the scope of the following claims will occur to those skilled in the art.

I claim:

1. A compass comprising a spherical enclosure at least part of which is transparent, transparent liquid disposed in said enclosure, a pivotally mounted support member inside said enclosure, a magnet-carrying compass card pivotally carried by said support member thereabove, and a sealed gas-filled compression chamber carried by said support member below said compass card, said compass including a soft, yieldable foam member cupping and carrying said enclosure and a rigid skin member around said foam member, said skin member including a hole-defining edge seated in a groove of said foam member, said foam member including a hole with therearound a reversely directed lip defining with the main body of said foam member said groove, and less than half of said enclosure protruding upwardly through said foam member hole, the latter being of diameter less than the outer diameter of said enclosure, whereby said enclosure is insulated against shocks and compass card stability is improved.

2. The compass of claim 1 in which the inner spherical surface defining said spherical enclosure is free from open relieved portions with liquid-propelling surfaces.

3. A compass comprising a spherical enclosure at least part of which is transparent, a body of transparent liquid enclosed by said enclosure, a support member pivotally mounted in said enclosure and contactingly surrounded by said body, a magnet-carrying compass card pivotally mounted in said support member and contactingly surrounded by said body, and a gas-filled compression chamber carried by said support member, said chamber being surrounded by said body and holding said gas out of contact with said liquid, whereby an effect on undesirable impingements of currents within said body on said compass card is produced resulting in great stability.

4. A compass comprising a spherical enclosure at least part of which is transparent, transparent liquid disposed in said enclosure, a pivotally mounted support member inside said enclosure, a magnet-carrying compass card pivotally carried by said support member thereabove, and a sealed gas-filled compression chamber carried by said support member below said compass card, whereby improved compass card stability is achieved, said compass including an upwardly-extending jeweled shaft rigidly carried by said support member, a compass card pivot pin supported thereby, and an assembly bushing rigidly carrying said compass card pivot pin, said magnet being positioned beneath the compass card and provided with a pair of elongated ends and a central generally cylindrical portion, said compass card including a central hole therethrough, and said bushing including a downwardly extending slotted annular shank, abutment surfaces adjacent said shank engaging the upper surface of said compass card and said shank extending through said central hole of said compass card, gripping said cylindrical portion of said magnet, and accepting said

elongated ends through the slotted portion, said magnet and said jeweled shaft cooperating to permit limited upward movement of said magnet relative to said jeweled shaft, whereby said pivot pin, bushing, compass card, and magnet are held in rigid unitary relationship for desired movement relative to said jeweled shaft and said support member carrying the same.
